RAILWAY TRAFFIC CONTROLLING APPARATUS

Ralph R. Kemmerer, Swissvale, Pa., assignor to
The Union Switch & Signal Company, Swiss-
vale, Pa., a corporation of Pennsylvania

Application September 6, 1930. Serial No. 480,161
Renewed April 16, 1932

36 Claims. (Cl. 246—33)

My invention relates to railway traffic controlling apparatus for utilizing coded current in track circuits for the control of signals which may be either wayside signals or train carried signals or both, and more particularly it relates to apparatus for utilizing coded current in the running rails and/or line circuits for establishing directional control on a single track railway.

I will describe one form of apparatus embodying my invention, and will then point out the novel features thereof in claims.

The accompanying Figs. 1^a, 1^b and 1^c, when placed end to end in the order named, with Fig. 1^a on the left, form a diagrammatic view showing one form of apparatus embodying my invention.

In the accompanying drawings, like characters of reference designate corresponding parts, an exponent being added to the reference character to distinguish the location of the part.

In the description, I shall assume the left-hand end of the figures to be west and the right-hand end to be east, and I shall speak of a train traveling from the right to the left as a westbound train, and one traveling from the left to the right as an eastbound train.

The reference characters 1 and 2 designate the track rails of a stretch of single track railway extending between two passing sidings P¹ and P². These rails are divided by customary insulated rail joints 3 into the track sections V—W, W—X, etc., and while in the drawings, the stretch of track between the two sidings is shown arranged with only two intermediate track sections, it will be understood that any number of such track sections may be employed.

The energy for the operation of the apparatus is furnished by line transformers G, one of which is located at each junction of adjacent track sections. The primary 7 of each of these transformers is connected to a transmission line E, which is constantly supplied with alternating current of a convenient commercial frequency such as 60 cycles per second from a source which is not shown in the drawings.

An auxiliary transformer M is located at each junction of adjacent track sections, and its primary 8 is connected to the secondary 9 of the associated transformer G. The secondary 10 of each transformer M is connected to the input terminals of a rectifier 11 which furnishes direct current for the operation of certain parts of the apparatus of my invention.

Each track section is provided with a two-element track relay TR which has a track wind-

ing 12 connected across the rails at one end of the track section and a second winding 13 constantly supplied with alternating current from the secondary 9 of the associated transformer G. The track winding 12 of each track relay TR is connected in series with a secondary winding 14 of an associated impedance transformer T1, and connected directly across the track rails is the secondary winding 15 of a code feeding transformer T2 in series with a current limiting reactor 16 all of which will be later described.

Each track relay of my invention is so designed as to be responsive to the code impulses received from the track circuit and connected in such a manner as to not respond to the coded energy when supplied by the associated code feeding transformer T2. The particular function of each track relay, the associated impedance transformer, and the code feeding transformer will be brought out in detail as the description progresses.

A master line relay MR is located at the junction of adjacent track sections, and each line relay MR is supplied with coded energy over a pair of line wires 17 and 18 in accordance with certain traffic conditions as will be hereinafter pointed out.

Each track section is provided with a track transformer T, the secondary 19 of which is connected through the usual current limiting reactance 20 across the rails of the section at the end opposite from the track relay TR. The primary 21 of each track transformer T is supplied with alternating current from an associated transformer G which current is periodically interrupted or coded at the rate of 40, 80 or 180 cycles per minute or any other code frequency desired, and it follows that when any given track section is unoccupied, the track relay of that section is operated at the rate of 40, 80 or 180 cycles per minute, except under certain specific conditions to be pointed out later.

Each track section is provided with a code transmitter CT including a motor element 22 (see Fig. 1^b) constantly supplied with direct current by the rectifier 11 of the same location. This code transmitter is to be of any of the standard types commonly used for this kind of work and, as the specific structure of the code transmitter or the manner whereby it actuates contacts at different speeds form no part of my invention in this specification, it will be understood that both upper contacts 23 and 24 periodically close their respective front and back contacts at a rate of 180 times per minute, that both

center contacts 25 and 26 close their respective front and back contacts at a rate of 80 times per minute, and that both the lower contacts 27 and 28 close their respective front contacts at 5 a rate of 40 times per minute.

Each track relay controls decoding apparatus involving three relays TP, 2H and 2D in such a manner that these relays are selectively responsive to the three code rates specified. This decoding device includes a transformer 2DT, the primary 30 of which is supplied with direct current from the associated rectifier 11 through an armature 31 of the associated relay TR. When the associated track relay TR is energized, current flows from the upper or positive terminal of the rectifier 11 (see Fig. 1^a) along positive wire B, front contact of armature 31 of the relay TR, the right-hand half of the primary winding 30 of the transformer 2DT^V, center tap, and wire C to the lower or negative terminal of the rectifier 11. When the relay TR is deenergized, current flows through the back contact of the armature 31 to the left-hand half of the primary 30 and back to the negative terminal of rectifier 11. It follows then, that with the track relay operated by a coded current, an alternating voltage is induced in the secondary 35 of the decoding transformer 2DT, the frequency of which is the same as the frequency of operation of the track relay, while with the track relay either continuously energized or continuously deenergized no voltage is induced in the secondary of the decoding transformer. A condenser 36 may be connected across the primary 30 of transformer 2DT to reduce the sparking at the contacts of the armature 31 of relay TR. Each transformer 2DT is provided with a first secondary circuit (see Fig. 1^a) which includes a reactor 37 and a rectifier 38 in series. The output terminals of this rectifier 38 are connected with decoding relay TP^V. The parts of this circuit are so proportioned and adjusted that relay TP^V will respond to any one of the three codes but most efficiently to the 40 code. Transformer 2DT is provided with a second secondary circuit which includes a reactor 39 in series with three condensers 41, 42 and 43 in multiple, while a rectifier 44 is connected in shunt with a part of the reactor 39. A decoding relay 2HV is connected to the output terminals of the rectifier 44, and the parts of this circuit are so proportioned that the relay 2HV responds only to the code of 80 cycles per minute. A third secondary circuit is connected to the secondary 35 of the transformer 2DT including a reactor 45 and a condenser 46 in series. A rectifier 47 has its input terminals connected across a portion of the reactor 45 and the output terminals of the rectifier are connected with the decoding relay 2DV. The parts of this circuit are so proportioned that the relay 2DV responds only to the code of 180 cycles per minute. A slow-acting repeater relay, designated by the reference character 2PV, together with a thermal unit TU, whose function is to retard the pick-up of the relay 2PV, are associated with the decoding relays 2HV and 2PV by a circuit consisting of positive terminal of the rectifier 11, positive wire B, wire 48, front contact 49 of relay 2DV, wire 50, front contact 53, coil of relay 2PV, wire 54, and negative wire C to the negative terminal of the rectifier 11, or in place of the front contact 49, this circuit may branch from wire 48, through the front contact 57 of the relay 2HV, to the wire 50, and then as before traced. It will be noted that

this is a stick circuit which requires that the associated thermal unit TU, which is connected in circuit when the relay 2PV is deenergized closing its back contact 55, must first be heated. The circuit for heating the element 56 of the thermal unit TU extends from the positive terminal of rectifier 11, wire B, wire 48, either front contact 49 of relay 2DV or front contact 57 of relay 2HV, wire 50, back contact 55, heating element 56, and wires 54 and C to the negative terminal of rectifier 11. As soon as the heating element 56 heats up so as to close its contact 58, a pick-up circuit is established through the contact 58 to the relay 2PV that is the same as traced for the heating element 56 up to wire 50 thence by contact 58, winding of relay 2PV and wires 54 and C to the negative terminal of rectifier 11. With relay 2PV once up, it closes the stick circuit above traced, and opens the circuit to the heating element 56 at the back contact 55. 30 35 40 45 50 55 60 65 70 75 80 85 90 95

Each master line relay MR controls a decoding apparatus including the decoding relays MP, 1D, 1H, a decoding transformer 1DT, and a slow-acting repeater relay 1P with an associated 100 thermal unit in exactly the same manner as described for the decoding transformer, relays, etc., associated with the track relay TR. Thus it is considered sufficient to say that relay MP responds to any of the codes 40, 80, and 180 but 105 most efficiently to the 40 code, that the relay 1H responds only to the 80 code and that the relay 1D responds only to the 180 code.

At the junction of adjacent track sections there are provided directional stick relays indicated by the reference characters 1S and 2S with an appropriate exponent. These stick relays perform functions similar to those of the directional stick relays used in standard absolute permissive block signal systems, that is, to 110 establish directional control and permit following train movements. As the manner of selecting the directional relay is the same at each location, only one location will be described and I shall use Fig. 1^b. The pick-up circuit for the 115 directional relay 1SW associated with westbound traffic extends from the positive terminal of the rectifier 11, along positive wire B, wire 59, back contact 60 of relay 2PW, wire 61, back contact 62 of directional relay 2SW, wire 63, back contact 64 of relay MP^W, wire 65, front contact 66 of relay 1PW, wire 67, relay 1SW, and wires 68 and C to the negative terminal of rectifier 11. The stick circuit for this directional relay 1SW extends from wire 65, along wire 70, front contact 69 of the 120 relay 1SW, to wire 67. The directional relay 125 2SW associated with eastbound traffic is provided with a similar pick-up circuit that extends from the positive terminal of rectifier 11, along wire B, wire 71, back contact 72 of relay 1PW, wire 73, back contact 74 of directional relay 1SW, wire 75, back contact 76 of relay TP^W, wire 77, front contact 78 of relay 2PW, wire 79, coil of relay 2SW, and wires 80 and C to the negative terminal of rectifier 11. The stick circuit for relay 2SW 130 branches from wire 77, along wire 81, front contact 82 of the relay 2SW to the wire 79. 135 140 145 150

Each section is provided with a wayside signal located at each end of the section and these signals govern traffic in opposite directions through the section. Signals governing eastbound traffic are designated by the reference character R with an exponent corresponding to the location, while the signals governing westbound traffic are designated by the reference character L with an ex- 150

ponent corresponding to the location. These wayside signals may be any of the standard types and are here shown as three-position light signals. The lighting circuits of each signal are controlled by the decoding relays for the corresponding section, and as the light circuits of all signals are alike, a description of any one will be sufficient for the understanding of all. Referring to signal RW the proceed light circuit is from one terminal of secondary 9 of transformer GW along wire BX110, wire 83, front contact 84 of relay TPW, wire 85, front contact 86 of relay 2PW, wire 87, back contact 88 of relay 2HW, wire 89, front contact 90, wire 91, proceed light G, and wires 92 and CX110, to the opposite terminal of secondary 9. The caution light circuit for signal RW is the same as that just traced for the proceed circuit up to wire 87, and then by front contact 93 of relay 2HW, wire 94, caution light Y, and wires 92 and CX110 to secondary 9. The stop light circuit for the signal RW may be energized by a circuit branching from wire 83, back contact 95 of relay TPW, wire 96, stop light R, and wires 92 and CX110 to the secondary 9, or it may be energized by a circuit branching from wire 85, back contact 97 of relay 2PW to the wire 96, and as before, or once again it may be energized by a circuit branching from wire 89 by back contact 98 of relay 2DW to the wire 93, and as before traced.

Having pointed out the various devices with which each track section of my invention is provided, I shall now describe its operation, and I shall first assume that all track sections between the two sidings are unoccupied. Normally coded, alternating current is supplied to the track rails of each track section by the transformer T of the section inasmuch as the primary winding 21 of transformer T has one side connected by the common wire CX110 to one terminal of the secondary 9 of the transformer G, and its other terminal is connected to the opposite side of the secondary 9 over front contact 190 of the MP relay at that location, wire 101, front contact 102 of the 2P relay, wire 103, 180 code contact 24 of the code transmitter CT, and thence by wire BX110 to secondary 9. It follows then that each track relay TR will normally follow each 180 code cycle alternately closing the front and back contact of its armature 31. It has been already noted that the positive terminal of rectifier 11 is connected to the heel of the armature 31 by the positive wire B and also that the extreme ends of the primary winding 30 of the decoding transformer 2DT are connected to the front and back contacts, respectively, and that the center tap of the primary winding is connected to the negative terminal of rectifier 11 by the negative wire C. It follows then that with the front and back contacts of track relay TR alternately closed the half of the primary winding of the decoding transformer fed by the front contact will be energized for the duration of the "on" code period, thereby building up a flux in one direction and, when the "off" period of the code cycle occurs, the back contact closes and the other half of the primary winding 30 will be energized, but in the reverse direction from the first. This will cause the flux to build up in the first instance and to die down and build up in the opposite direction with each 180 code cycle. With the building up of a flux in one direction and the dying down and building up in the opposite direction, a voltage is induced in the secondary winding 35 of the decoding transformer with a frequency correspond-

ing to the code current energizing the relay TR, and, as just pointed out, under normal conditions this is the 180 code. As described earlier in the description, the secondary circuit feeding rectifier 47 is tuned to resonance at that frequency and, therefore, the 2D relay of each track section is normally energized. It also follows that the circuit for the decoding relay TP of each section being untuned and responsive to all codes will cause the TP relay to be normally energized. A resistance 165 may be placed in series with the coil of the relay TP when it is deenergized for the purpose of quickening the pick-up and by means of a front contact 106 this resistance is normally short-circuited to give full energization of the relay. It will be noted that the repeater relay 2P is normally energized by a circuit normally closed at the front contact 49 of the 2D relay and which circuit was traced in detail earlier in the description.

Thus we see that the track rails of each successive track section is normally supplied with 180 code energy, and that this energy is decoded to energize the relays TP and 2D and, in turn, to energize the relay 2P, and these relays select the circuit to supply 180 code energy to the next section to the left and to govern the operation of wayside signals.

I desire to here point out that if the coded energy supplied to the rails of a track section bc of the 80 code at which frequency the circuit for the relay 2H is tuned to resonance, the relay 2D at that location will drop and the relay 2H will be energized and the relays TP and 2P are each retained energized. It follows, therefore, that with the rails of a given track section supplied with current of the 80 code the circuit to supply 180 code current to the rails of the track section to the left is closed.

With current of 40 code supplied to the rails of a track section, the relay TP of that section is retained energized but both the 2H and 2D relays of the section are deenergized and, in turn, the associated repeater relay 2P is deenergized. This results in the closing of the 80 code circuit, if the directional relay 2S is up, to the track section to the left, or in closing the 40 code circuit in the event the directional relay 2S is down. Referring to Fig. 1b, the circuit to supply the 80 code current is from the secondary 9 of transformer GV, wire BX110, 80 code contact 26, wire 99, front contact 108 of directional relay 2SW, wire 148, back contact 147 of relay 2PW, wire 101, front contact 100, primary 21, and the wire CX110 to secondary 9. The circuit to supply the 40 cod- 125 is from the secondary 9 by wire BX110, 40 code contact 28, wire 150, back contact 149, and then as traced for the 80 code circuit.

With each successive track section normally supplied with coded energy in the manner similar to that just described, it becomes apparent that this coded track current affords a means of controlling wayside signals governing traffic in one direction, and also to control train carried apparatus receiving current inductively from the track rails such, for example, as the apparatus disclosed and claimed in an application for Letters Patent of the United States, filed by P. N. Bossart, on the 7th day of February 1927, Serial No. 166,407, when said train is traveling in one direction. It is also apparent that the making use of the same principle of coding and decoding of alternating current and then applying such to a pair of line wires, gives a means of operating as many relays as required to control the appli- 150

cation of train governing current to the rails and to control wayside signals for governing traffic in the opposite direction from that permitted by the current normally fed to the rails by track 5 transformers. I will now describe the operation of such line circuits.

The master relay MR, as in the case of track relay TR, is a two-element relay. One element 112 is continuously supplied with alternating current by the wires BX110 and CX110 from the secondary 9 of the associated transformer G as will be apparent from the drawings. The second element 117 of the MR relay is supplied with coded current from the next block to the left 10 over the line wires 17 and 18. Taking the case 15 of relay MR^W, the normal circuit for supplying the 180 code current extends from one side of secondary 9 of transformer GV along wire BX110, 180 code contact 24 of code transmitter CTV, 20 wires 103 and 113, front contact 114 of the relay 1PV, wire 115, front contact 116 of relay TPV, 25 wire 18, element 117 of relay MR^W, wire 17, and wire CX110 to the opposite terminal of secondary 9. Under certain traffic conditions, as will be 30 pointed out later, the relay MR^W is supplied with either 80 code or 40 code current. The circuit to supply 80 code energy to the element 117 of relay MR^W may take either of two paths, the first being from the secondary 9 of the transformer GV, through 80 code contact 26 of code transmitter CTV, wire 119, back contact 120 of MPV, wire 121, back contact 122 of relay 1PV, and then as before traced for the 180 code current. 35 The second path extends from secondary 9 through 80 code contact 25 of CTV, along wire 126, front contact 127 of relay MPV, wire 121, and as before traced. The circuit to supply the element 117 of relay MR^W with 40 code current is from secondary 9 of GV through 40 code contact 40 28 of CTV, a front contact 123 of directional relay 2SV, back contact 124 of relay TPV and then as before traced for 180 code current. It is to be noted that at intermediate signal locations, 40 code current is supplied to the master line relay 45 to the right when the MP relay at the intermediate location is up and the 1P relay is down, instead of 80 code current as just described at the leaving location V. Looking at Fig. 1^b, 40 code current is supplied to the master line relay MR^X 50 through the 40 code contact 27 of code transmitter CTV by a circuit which includes front contact 109 of relay MP^W, back contact 155 of relay 1PW and front contact 151 of relay TP^W.

The explanation of the decoding apparatus 55 given for the decoding relays TP, 2H and 2D is identically the same for the decoding relays 1D, 1H and MP, and the function of the repeater relay 1P is similar to that described for the repeater relay 2P. These decoding relays associated with the master line relay control wayside 60 signals governing traffic in a direction opposite to the signals controlled by the decoding relays associated with the track relay TR. These decoding relays associated with line relay MR also 65 control the application of train governing current to the track rails, at the track relay end of each track section when that end becomes an exit end, by means of the code feeding transformer T2, as will be shortly pointed out.

I will now describe the operation of the apparatus for a train moving from the left to the right, that is, an eastbound train, and I shall assume that this train has entered the track section to the left of the signal RV. The relay 70 MR^V will receive no code due to the track relay

being down. Because of the absence of 180, 80 or 40 code, the relays 1DV, MP^V and 1HV will be deenergized, deenergizing, in turn, the relay 1PV. With the deenergizing of the 1DV, MP^V and 1HV relays, at the leaving signal of the passing siding P1, the MR relay at the first intermediate signal location, that is, relay MR^W, is caused to operate on 80 code current by the circuit previously traced, and which includes the back contact 120 of relay MP^V and back contact 122 of the 1PV relay. The MR^W relay being thus operated on 80 code, a caution signal is displayed by signal LW. With the train advancing into the block V—W past signal RV in a clear position, the first pair of wheels shunt the track relay TR^V and relays TPV, 2HV, 2DV and 2PV all become deenergized. The deenergizing of relay TPV opens the contact 116 and thus shuts off the 80 code to the relay MR^W. However, relay 2PV being slow-releasing will not open its front contacts until sometime after relay TPV has closed its back contacts, and thus effect the energization of the directional stick relay 2SV, the pick-up circuit for relay 2SV being similar to that previously described for the directional relay 2SW. With the energizing of the relay 2SV, the line relay MR^W is supplied with 40 code energy from the secondary 9 of transformer GV, through the 40 code contact 28 of CTV by the circuit previously traced and which includes the front contact 123 of directional relay 2SV. With the relay MR^W thus operating on 40 code, its associated relays 1DW, 1HW, and 1PW are all down, and it follows, therefore, that each successive MR relay to the next passing siding is caused to operate on 40 100 code current, and this will cause all the west-bound signals to assume the stop position. With the deenergizing of the TPV relay and the energizing of the directional relay 2SV, it will be noted that it is necessary for the directional relay 2SV to pick up and to stick up in order to maintain train governing current on the track in advance of a train by the track transformer TV. It will also be noted that with relay 2SV up, 105 80 code energy is supplied to the track of the section to the left of the track section V—W, the circuit including the back contact 107 of relay 2PV. It follows that a caution indication will be displayed by the next signal in the rear of signal RV, the signal RV having assumed a stop 110 position as the train entered the track section V—W. With the train advancing from section V—W into the track section W—X, the 40 code continues to be supplied to the MR relays in 115 advance of a train, and 80 code current will now be supplied to the rails of the section V—W, and 180 code to the rails of the section to the left of V—W. It will be observed that while the train occupied the track section V—W, the impedance transformer T1V has its primary winding 120 short-circuited through back contact 129 of relay TPV, back contact 130 of relay 1PV, and a front contact 131 of relay MP^V, and this short-circuiting results in the secondary winding 14 offering small impedance to the coded 125 energy thereby permitting the relay TR^V to readily respond to the 80 code impulses applied to the relay as the train leaves the section V—W. With the relay TR^V operated by 80 code energy, the relays TPV and 2HV will pick up and then, in 130 turn, relay 2PV. With relay 2HV picking up, the directional relay 2SV is deenergized, and with relay 2PV up, the track transformer TV will be supplied with 180 code through the front contact 102 of 2PV and the front contact 100 of 135 2P^V.

MP^V with the result that the signal to the left of R^V will be cleared in a manner previously described under normal conditions. With the de-energizing of directional relay 2SV, direct current is supplied from the rectifier 11 to the thermal unit associated with relay 1PV by a circuit including wire B, wire 132, front contact 133, wire 134, back contact 135, wire 136, back contact 137, heating unit 138, and wires 139 and 10 C to the negative terminal of rectifier 11. After the closing of the contact 140 of the thermal unit, the relay 1PV becomes energized, and the energizing of relay 1PV permits signal L^V to clear.

15 The operation of the train advancing to the right and entering each successive track section is similar to that just described for the train traveling from section V—W into section W—X. In summing up the operation for an eastbound 20 train, we find that all opposing westbound signals are set at stop to the next passing siding, that coded energy is supplied to the track rails at the exit end of each track section by means of the track transformer T, that this coded energy is varied in accordance with the number 25 of unoccupied track sections in advance of the train, and that this coded current controls wayside signals to govern the train and is also adapted to control train carried cab signals, and that the directional relays assure that proper 30 code energy is supplied to the rails of the track section to the rear of the train to permit following train movements and also to provide the clearing of the opposing wayside signals behind 35 the train.

I shall describe next the operation of a westbound train and, as before, I shall assume that all 40 track sections between the sidings are unoccupied and that the train occupies the track section to the right of section W—X. By the train occupying section W—X, it shunts the track relay TR^X and concurrently relays TP^X, 2H^X and 2D^X are deenergized, and, in turn, the repeater relay 45 2P^X is deenergized. This results in 80 code energy being applied to the track circuit of section W—X as follows: Secondary 9 of transformer GX, wire BX110, 80 code contact 26 of code transmitter CT^X, wire 250, back contact 51, front contact 100 of relay MP^X, primary 21, and wire CX110 50 to secondary 9. It follows then that as the train occupies the section to the right of W—X, that the eastbound signal R^X is at stop and the first intermediate signal R^W is at caution.

As the train advances into section W—X and 55 shunts the track relay TR^W, the relay TP^W now becomes deenergized and with relay TP^W deenergized, code energy is supplied to rails of the section W—X at the exit end by means of the code feeding transformer T2^W in the following manner. One side of the primary 235 is connected to one terminal of secondary 9 of transformer GW by the wire CX110 and the other side of primary 60 235 is connected to the other terminal of secondary 9 over wire 236, back contact 237, wire 238, front contact 239, wire 240, 180 code contact 23 of code transmitter CT^W and wire BX110. It will be noted that wire 236 is also connected to one side of the primary 141 of the impedance transformer T1^W and that the other side of the primary 141 is connected to a back contact 142 of code transmitter CT^W by wire 143. Thus we have code energy fed to the rails when the front contact of the code contact 23 is closed and during the interval when the back contact 142 is closed no code is being fed to the rails and the primary

141 of T1^W is short-circuited. This short-circuiting of the primary of the impedance transformer T1^W is to permit relay TR^W to pick up with the first impulse of energy supplied to the relay by the track transformer TX when the train leaves the section.

Furthermore, the train governing code energy fed to the rails by the code feeding transformer T2^W is in the reverse direction from that supplied by the normal track transformer TX, and it follows that what small energy reaches the element 12 of track relay TR^W through the impedance transformer T1^W is in a direction to hold the relay TR^W down.

This 180 code energy applied to the rails of the track section W—X by the code feeding transformer T2^W controls the train carried cab signal.

With the deenergizing of relay 2PW, the coded energy supplied to the primary 21 of track transformer T2^W controls the train carried cab signal.

With the deenergizing of relay 2PW, the coded energy supplied to the primary 21 of track transformer T^W will be delivered over the circuit including front contact 100 of relay MP^W, wire 101, back contact 147, wire 148, back contact 149, wire 150, 40 code contact 28 of code transformer CT^W, and wire BX110 to secondary 9 of G^W, and from the other terminal of secondary 9 to primary 21 by wire CX110.

Thus with the train in the section W—X, 40 code energy is supplied to the track circuit of section V—W which will cause relays 2HV, 2DV and 2PV to become deenergized with the result that signal R^V is set at stop and in the event signal R^V is an intermediate signal, 40 code energy is supplied to the rails of the next section to the left and so on until each successive intermediate signal to the next siding is set at stop.

The 40 code energy will, in each case, retain the TP relay energized until the westbound train enters the section when it will become deenergized and train governing current dependent upon traffic conditions in advance will be supplied to the rails at the exit end of that section by means of the code feeding transformer T2 in a manner similar to that just described for the section W—X.

As the train entered section W—X, the deenergization of relay TP^W opened the circuit to the line relay MR^X at contact 151, and as the directional relay 2SW remains deenergized, consequently, the relay MR^X receives no energy and the result is that relays 1DX, 1HX, MP^X and 1PX all become deenergized, and the signal L^X set in the stop position.

It will be noted that with the deenergization of the relay MP^X, the wire BX110 is connected directly to the primary 21 of the track transformer TX through the back contact 152, and it follows then that the primary 21 is fed uncoded alternating current during the time the section W—X is occupied by a westbound train; also, such would be the case for just an instant after a momentary short-circuit or an instant after a power failure.

It follows that as the westbound train vacates section W—X, uncoded alternating current is fed to the section W—X and the track relay TR^W given an impulse to close its front contact.

This impulse results in a change of flux in the decoding transformer 2DT^W to induce one-half cycle of alternating current in the secondary of 2DT^W which will pick up relay TP^W and with relay TP^W up, the MR^X relay will be operated with 80 code current as follows:

Secondary 9 of G^W, wire BX110, 80 code contact 26 of CT^W, front contact 153 of directional relay 1SW, relay 1SW having been picked up as the train entered the

100 train.

section V—W, back contact 154, back contact 155, front contact 151, line wire 18, relay MR^x , line wire 17, and wire CX110 to the other terminal of secondary 9. This results in relay MR^x picking up to feed a code to the circuit of primary 21 of T^x , continuing therefore, the energization of relay TP^w by the operation of the track relay TR^w on code.

As the westbound train entered section V—W, it shunted the track relay TR^v with the result that the TP^v relay drops to open the circuit to relay MR^w at the front contact 116. The relay MR^w being now deenergized, the associated relays $1D^w$, $1H^w$, MP^w and $1P^w$ are all deenergized. However, as $1P^w$ is slow-releasing, the directional relay $1S^w$ will be picked up as stated above, by a circuit which includes the front contact 66 of $1P^w$ and the back contact 64 of relay MP^w , and once relay $1S^w$ is up, it is held up by its stick circuit. The deenergizing of relay $1P^w$ causes the westbound signal L^w to assume a stop position. With directional relay $1S^w$ up, and 80 code energy supplied to the relay MR^x as just described, it follows that the westbound signal L^x will assume a caution position, and that the next signal to the rear of signal L^x will display a proceed indication. The operation of the train entering and traveling section V—W will be the same as that described for section W—X and likewise each successive section to the next siding. It will be observed that code energy is fed by the track transformer T to the rails of the track section to the rear of the westbound train; however, if a second westbound train follows this first train, 40 code current will be fed to the track circuit and the eastbound R signals set at stop. It will also be noted that if a second westbound train enters the section W—X, while the first train occupies the section V—W, 80 code energy is supplied to the rails of section W—X by the code feeding transformer $T2^w$ in place of the 180 code energy described in connection with the first train. This 80 code energy is supplied to the transformer $T2^w$ from the secondary 9 of transformer G^w over wire BX110, 80 code contact 25 of code transmitter CT^w , front contact 111 of directional relay $1S^w$, back contact 156, back contact 157, back contact 237, wire 236, primary 235 of $T2^w$, and wire CX110 to secondary 9, and this 80 code energy thus supplied to the section W—X will establish a caution cab signal for the second westbound train.

To sum up the operation for a westbound train, we find that 40 code energy is applied to the track of all track sections to the next siding with the result that all eastbound signals are set to stop, that as a train enters a section, train governing code current is applied to the rails at the exit end of the section to control train carried devices, that the westbound signals to the rear of the train are controlled by code energy applied to the master line relay, that the directional relays provide protection for following trains, and that the apparatus is responsive to traffic conditions in advance of a train.

Such a system herein disclosed and described is practically immune from propulsion alternating current or direct current or any other form of electrical energy that may be used in the running rails. The coded line circuit reduces the possibility of inductive interference from commercial power lines to a remote possibility. Such a system also reduces the first cost of that of present day systems in that it reduces to a minimum the number of line wires required. Furthermore,

such a system will operate equally as well for wayside signals alone or train carried cab signals alone or for both wayside signals and cab signals.

Although I have herein shown and described only one form of railway traffic controlling apparatus embodying my invention, it is understood that various changes and modifications may be made herein within the scope of the appended claims without departing from the spirit and scope of my invention.

Having thus described my invention, what I claim is:

1. A combined wayside and cab signal system for railways including a stretch of trackway over which traffic may move in either direction, a wayside signal located at each end of the stretch to govern traffic through the stretch, means located at each end of the stretch to supply to the rails train governing coded current of different codes adapted to govern the operation of train carried cab signals, trackway means selectively responsive to the different codes of the said coded current to govern the operation of said wayside signals, and directional means effective when a train occupies the stretch traveling in either direction to selectively control the supply of coded current of different codes to the rails of the stretch at the end in advance of the train in accordance with traffic conditions ahead.

2. A combined wayside and cab signal system for railways including, a stretch of trackway over which traffic may move in either direction, a wayside signal located at each end of the stretch to govern traffic through the stretch, means located at each end of the stretch to supply to the rails alternating current periodically interrupted at different rates adapted to govern the operation of train carried cab signals, trackway means selectively responsive to the different rates of the periodically interrupted alternating current to govern the operation of the said wayside signals, and directional means effective when a train occupies the stretch traveling in either direction to selectively control the supply of the said periodically interrupted alternating current to the rails of the stretch at the end in advance of the train in accordance with traffic conditions ahead.

3. A railway signal system including a stretch of trackway over which traffic may move in either direction, a wayside signal located at each end of the stretch to govern traffic through the stretch, means located at each end of the stretch to supply to the rails coded alternating current of different codes, trackway means selectively responsive to the different codes supplied to the rails to govern the operation of the signals and to selectively control the supply of said coded current to the rails of the stretch in accordance with traffic conditions on either side of said stretch.

4. A railway signal system including a stretch of trackway over which traffic may move in either direction, a source of alternating current, means associated with said source to normally supply alternating current to the rails adjacent one end of the stretch periodically interrupted at different rates, a track relay connected to the rails at the end opposite from said means responsive to alternating current periodically interrupted, decoding relays associated with the track relay, means to selectively energize said decoding relays in accordance with the rate of interruptions of

- the alternating current supplied to the track relay, traffic controlled means to control said rate of interruptions in accordance with traffic conditions on either side of said stretch, and wayside 5 signals to govern traffic in opposite directions through the stretch controlled by said decoding relays.
5. In a railway signal system including a stretch of single track railway arranged in track 10 sections, a signal located at each end of the stretch to govern trains traveling through the stretch, a source of train governing coded current of different codes located at each end of each track section to supply coded current to the rails 15 adapted to govern train carried devices on trains traveling in opposite directions through the stretch and arranged that at least one of the sources of each section is normally effective to supply coded current to the rails, a track relay 20 for each section responsive to such coded current, a plurality of decoding relays associated with each track relay, means to selectively energize said decoding relays in accordance with the code with which the track relay is operated, and 25 directional means controlled by said decoding relays for governing the signals and for selecting the code to be supplied to the rails of each track section in accordance with the direction of movement of the train as it travels said stretch of single track.
6. In combination, a trackway arranged in track 30 sections, a track circuit for each section, a line circuit for each section controlled by the track circuit, a line relay having a winding connected 35 with the line circuit and responsive to periodic interruptions of alternating current in said line circuit, a plurality of decoding relays associated with said line circuit, means for selectively energizing said decoding relays in accordance with 40 the rate of operation of the associated line relay, means controlled by the decoding relays of the line circuit for supplying alternating current to the line circuit of an adjacent track section periodically interrupted at different rates according 45 to the conditions of the decoding relays, and signals controlled by the decoding relays.
7. In combination, a trackway arranged in track 50 sections, a track circuit for each track section, a line circuit for each section controlled by the track circuit, a line relay responsive to coded energy in 55 said line circuit, a plurality of decoding relays associated with said line circuit, means controlled by said line relay for selectively energizing said decoding relays in accordance with the coded energy supplied to the associated line circuit, means controlled by the decoding relays of the line circuit for supplying coded energy of 60 different codes to the line circuit of an adjacent track section according to the conditions of the decoding relays, and signals controlled by the decoding relays.
8. In combination, a trackway arranged in track 65 sections, a track circuit for each track section, a line circuit for each section controlled by the track circuit, a line relay responsive to coded energy in 70 said line circuit, a plurality of decoding relays associated with said line circuit, means controlled by the line relay for selectively energizing said decoding relays in accordance with the coded energy supplied to the associated line circuit, means controlled by the decoding relays of the line circuit for supplying coded energy of different codes to the line circuit of an adjacent track section according to the conditions of the decoding 75 relays, and other means controlled by the decoding relays for supplying coded train governing energy of different codes to the rails of said adjacent track section according to the conditions of the decoding relays.
9. In combination, a stretch of railway over 80 which traffic may move in either direction arranged into a plurality of track sections, a line circuit for each track section responsive to traffic conditions of the section, a line relay for each section responsive to coded energy in said line circuit, a decoding relay associated with each line relay and energized only when the line circuit is supplied with coded energy of a given code, means to normally supply the line circuit with coded energy of said given code, a signal for each section to govern traffic in one direction through the section controlled by the decoding relay and adapted to display a proceed signal when said decoding relay is energized, and a traffic controlled means responsive to a train entering the stretch traveling in a direction opposite to that governed by the signal to cut off the normal supply of coded energy from the line circuit of each track section of the stretch.
10. In combination, a stretch of railway over 100 which traffic may move in either direction arranged in a plurality of track sections, a line circuit for each track section, responsive to traffic conditions of the section, a line relay for each line circuit responsive to coded energy, a first and a second decoding relay associated with each line relay respectively energized only when the line circuit is supplied with coded energy of a first or a second code, a signal controlled by said decoding relays to govern traffic through the section in 110 one direction adapted to display a proceed signal when the first decoding relay is energized and to display an approach signal when the second decoding relay is energized, and traffic controlled means responsive to a train entering the stretch 115 traveling in a direction opposite to that governed by the signal to prevent the line circuits of the plurality of track sections being supplied with coded energy of either said first code or said second code.
11. In combination, a stretch of railway over 120 which traffic may move in either direction arranged into a plurality of track sections, a line circuit for each track section, a line relay for each line circuit responsive to coded energy, coding means for each section to supply coded energy of a first code or of a second code to the line circuit and arranged to normally supply coded energy of the first code; a first and a second decoding relay associated with each line relay, with 125 the first decoding relay energized only when the line relay is operated by coded energy of the first code and the second decoding relay energized when the line relay is operated by either code; a signal for each section controlled by the first decoding relay, means controlled by the second decoding relay to control the line circuit for the track section to the rear, and traffic controlled means to discontinue the normal supply of coded energy of the first code and to supply coded energy of the second code to the line circuit of each track section of the stretch in response to a train 130 entering the stretch at a given end of the stretch.
12. In combination, a stretch of railway over 135 which traffic may move in either direction arranged in track sections, a line circuit for each track section, a line relay connected to each line circuit responsive to coded energy, a decoding relay associated with each line relay energized only when said line relay is operated by coded 140 energy.
13. In combination, a stretch of railway over 145 which traffic may move in either direction arranged in track sections, a line circuit for each track section, a line relay connected to each line circuit responsive to coded energy, a decoding relay associated with each line relay energized only when said line relay is operated by coded 150 energy.

energy of a given code, a signal for each track section controlled by the decoding relay adapted to display an approach signal when the decoding relay is energized, circuit means to supply the line circuit with coded energy of said given code but normally ineffective, and directional selective means to render said circuit means of a given section effective to supply coded energy of the given code in response to a train entering the track section next in advance when traveling in the same direction as that for which the signal governs.

13. In combination, a stretch of railway over which traffic may move in either direction arranged in track sections, a line circuit for each track section, a line relay connected to each line circuit responsive to coded energy, a decoding relay associated with each line relay and energized only when said line relay is operated by coded energy of a given code, a signal for each track section controlled by the decoding relay adapted to display an approach signal when the decoding relay is energized, circuit means to supply the line circuit with coded energy of said given code but normally ineffective, a stick relay when energized to render effective said circuit means, and means to energize said stick relay in response to a train entering the track section next in advance when traveling in the same direction as that for which the signal governs.

14. In combination, a stretch of railway over which traffic may move in either direction arranged in track sections, a signal located at one end of each section to govern traffic through the section in one direction, track circuit means connected to the rails of each section at the end most remote from the signal to apply coded train governing energy to the rails, a line circuit for each section including a line relay responsive to coded energy, a decoding relay associated with each line circuit energized only when said line relay is operated by code energy of a given code to control the signal, coding means to supply said track circuit means and said line circuit with coded energy of said given code but normally ineffective, a stick relay when energized to render said coding means effective, and means to energize said stick relay in response to a train entering the track section next in advance when traveling in the same direction as that for which the signal governs.

15. In combination, a stretch of single track railway arranged into a plurality of track sections, a line circuit for each track section, a line relay for each line circuit responsive to coded energy, a decoding relay associated with each line circuit and energized only when said line relay is operated by coded energy of a given code, coding means to supply the line circuit with coded energy of said given code and normally effective, a signal for each section controlled by the decoding relay of the section to govern traffic in one direction through the stretch, and traffic controlled means to render the coding means ineffective to supply coded energy of said code to the line circuit of each section of the stretch in response to a train entering the stretch traveling in a direction opposite to that governed by the said signals.

16. In combination, a stretch of railway over which traffic may move in either direction arranged into a plurality of track sections, a track circuit for each track section, a track relay for each track circuit responsive to coded energy, coding means for each track section to supply

coded energy of either a first code or a second code to the track circuit and arranged to normally supply coded energy of the first code; a first and a second decoding relay associated with each track relay with the first decoding relay energized only when the track relay is operated by coded energy of the first code and the second decoding relay energized when the track relay is operated by either code; traffic controlled means responsive to a train entering the stretch at a given end of the stretch to discontinue the supply of energy of the first code to the track circuit of all track sections of the stretch in advance of the section occupied by the train and to supply energy of the second code thereto, and signaling means controlled by the decoding relays.

17. In combination, a stretch of single track railway arranged into at least three track sections, a track circuit for each track section, a track relay for each track circuit responsive to coded energy, coding means for each track section to supply coded energy of either a first code or a second code to the track circuit and arranged to normally supply coded energy of the first code, a signal located at one end of the stretch to govern traffic in one direction through the stretch, traffic controlled means responsive to a train entering the stretch at the end opposite from the signal to discontinue the supply of coded energy of the first code to the track circuit of each track section of the stretch and to supply coded energy of the second code to the track circuit of all track sections other than that occupied by the train, and means to control the signal adapted to establish a proceed indication in response to the track relay of each track circuit being operated by the first code and to establish a stop indication in response to the track relays being operated by the second code.

18. In combination, a stretch of single track railway arranged into at least three track sections, a track relay for each track section responsive to coded energy, coding means for each track section to supply coded energy of either a first code or a second code to the track relay and arranged to normally supply coded energy of the first code, a signal for each track section to govern traffic in one direction through the section, traffic controlled means responsive to a train entering the stretch traveling in a direction opposite to that governed by the signals to discontinue the supply of coded energy of the first code to the track relay of each track section of the stretch and to supply coded energy of the second code to the track relay of all track sections other than that occupied by the train, and means for each section to control the signal of that section controlled by the track relay and adapted to establish a proceed indication in response to the track relay being operated by the first code and to establish a stop indication in response to the track relay being operated by the second code.

19. In a railway signal system, a stretch of railway over which traffic may move in either direction arranged in track sections, a master line relay and a track relay for each track section each responsive to coded energy, means for each track section to normally supply coded energy of a given code to both of said relays, a traffic directional means to continue the supply of coded energy of the given code to the master line relay of each section only in response to a train entering the stretch at one end and to continue the supply of coded energy of the given code to the track relay of each track section only in response

to a train entering the stretch at the opposite end; and two signals for the stretch, one signal to govern traffic in one direction through the stretch and held in a clear position when the line relay of each section is operated by coded energy of the given code, and the other signal to govern traffic in the opposite direction and held in a clear position when the track relay of each section is operated by coded energy of the given code.

20. In a railway signal system, a stretch of railway over which traffic may move in either direction arranged in track sections, a track circuit and a line circuit for each track section, means for each track section to normally supply coded energy of a given code to the track circuit and to the line circuit of the section, a traffic directional means to continue the supply of coded energy of said given code to the track circuit only of each track section in response to a train entering the stretch at one end and to continue the supply of said given code to the line circuit only of each track section in response to a train entering the stretch at the opposite end; and two signals for the stretch, one signal to govern traffic in one direction through the stretch and held in a clear position when the line circuit of each section is supplied with coded energy of the given code and the other signal to govern traffic in the opposite direction through the stretch and held in a clear position when the track circuit of each track section is supplied with the given code.

21. In a railway signal system, a stretch of railway over which traffic may move in either direction arranged in track sections, a track circuit and a line circuit for each track section, a track relay for each track circuit and a master line relay for each line circuit, each of said relays being responsive to coded energy, means for each track section to normally supply coded energy of a given code to the track circuit and to the line circuit of the section, a traffic directional means to continue the supply of coded energy of said given code to the track circuit only of each track section in response to a train entering the stretch at one end and to continue the supply of said given code to the line circuit only of each track section in response to a train entering the stretch at the opposite end; and two signals for the stretch, one signal to govern traffic in one direction through the stretch and held in a clear position when the line relay of the line circuit of each section is operated by coded energy of the given code, and the other signal to govern traffic in the opposite direction through the stretch and held in a clear position when the track relay of the track circuit of each section is operated by the given code.

22. In a railway signal system, a stretch of railway over which traffic may move in either direction arranged in track sections, a track circuit and a line circuit for each section, a track relay for each track circuit and a master line relay for each line circuit each of said relays being responsive to coded energy, coding means for each track section to supply coded energy of different codes to the track circuit and to the line circuit of the section, a signal at each end of a section to govern traffic through the section, a first set of decoding relays associated with each track relay selectively energized in accordance with the coded energy supplied to the track circuit to control one signal according to the conditions of the said first set of decoding relays, and a second set of decoding relays associated with each master line relay selectively energized in accordance with the coded energy supplied to the line circuit to control one signal according to the conditions of the said second set of decoding relays.

23. In a railway signal system, a stretch of railway over which traffic may move in either direction arranged in track sections, a track circuit and a line circuit for each section, a track relay for each track circuit and a master line relay for each line circuit and each of said relays responsive to coded energy, coding means for each track section to supply coded energy of different codes to the track circuit and to the line circuit of the section, a signal at each end of a section to govern traffic through the section, a first set of decoding relays associated with each track relay selectively energized in accordance with the coded energy supplied to the track circuit to control one signal and the track circuit for the track section to the rear according to the conditions of the said first set of decoding relays, and a second set of decoding relays associated with each master line relay selectively energized in accordance with the coded energy supplied to the line circuit to control the other signal and the line circuit for the track section to the rear according to the conditions of the said second set of decoding relays.

24. In combination, a track section through which traffic may move in either direction, a first signal located at one end of the track section to govern traffic in one direction through the section, a first receiving and decoding means selectively responsive to coded energy of different codes to control said first signal, a second signal located at the opposite end of the section to govern traffic in the other direction through the section, a second receiving and decoding means selectively responsive to coded energy of different codes to control said second signal, and traffic controlled means to supply in accordance with traffic conditions, coded energy of different codes to said first and second receiving and decoding means.

25. In combination, a track section through which traffic may move in either direction, a first circuit means located at one end of the track section to supply to the rails coded train governing current to control traffic in one direction through the section, a first receiving and decoding means selectively responsive to coded current of different codes to control said first circuit means, a second circuit means located at the other end of the track section to supply to the rails coded train governing current to control traffic in the other direction through the section, a second receiving and decoding means selectively responsive to coded current of different codes to control said second circuit means, and traffic controlled means to supply in accordance with traffic conditions coded current of different codes to said first and second receiving and decoding means.

26. In combination, a track section over which traffic may move in either direction, a source of current located at each end of the section, coding means associated with each source adapted to supply train governing coded current of different codes to the rails of the section and arranged that one of said coding means is normally effective to supply current to the rails and the other of said coding means normally ineffective, a track relay connected to the rails of the section responsive to coded current, a plurality of decoding relays, means associated with the track relay to selectively energize said decoding relays in accordance with the code supplied to

the track relay, and circuit means controlled by the decoding relays to control the supply of train governing coded current to the rails of the track section on either side of said track section in accordance with traffic conditions.

- 5 27. In combination, a track section over which traffic may move in either direction, a signal located at each end of the track section to govern traffic through the section, a source of current located at each end of the section, coding means associated with each source adapted to supply train governing coded current of different codes to the rails of the section and arranged that one of said coding means is normally effective 10 to supply current to the rails and the other of said coding means normally ineffective, a track relay connected to the rails of the section responsive to coded current, a plurality of decoding relays, means associated with the track relay to selectively energize said decoding relays in accordance with the code supplied to the track relay, a first circuit means controlled by said decoding relays to control the operation of the said signals, and a second circuit means controlled by the decoding relays to control the supply of train governing coded current to the rails of the track section on either side of said track section in accordance with traffic conditions.
- 15 28. In combination, a track section over which traffic may move in either direction, a signal located at each end of the track section to govern traffic through the section, a source of current located at each end of the section, coding means associated with each source adapted to supply train governing coded current of different codes to the rails of the section and arranged that one of said coding means is normally effective to supply current and the other of said coding 20 means normally ineffective, a track relay connected to the rails of the section responsive to coded current, a plurality of decoding relays, means associated with the track relay to selectively energize said decoding relays in accordance with the code supplied to the track relay, a first circuit means controlled by said decoding relays to control the operation of the said signals, and a second circuit means controlled by the decoding relays to control the supply of train 25 governing coded current to the rails of the section in accordance with traffic conditions.
- 30 29. In combination, a track section over which traffic may move in either direction, a signal located at one end of the track section to govern traffic in one direction through the section, a second signal located at the other end of the section to govern traffic in the other direction through the section, a source of current located at each end of the section, coding means associated with each source to supply train governing coded current to the rails of the section and arranged that one of said coding means is normally effective to supply current and the other of said coding 35 means normally ineffective, a track relay connected to the rails of the section at the end opposite from the normally effective coding means and said relay responsive to coded current, a decoding relay, means associated with the track relay to energize said decoding relay when said track relay is operated by coded current, a first circuit means controlled by said decoding relay to control the operation of said signals, and a second circuit means controlled 40 by said decoding relay to control the supply of

train governing coded current to the rails by each of said coding means.

30. A railway signal system including, a stretch of traffic rails arranged in track sections, a track circuit for each section having a source of coded current connected across the traffic rails at one end of the section and a code following track relay connected across the rails at the opposite end of the section normally operated by the coded current, a decoding device, means to energize said decoding device in response to the track relay operated by coded current, and means controlled by the decoding device to supply coded current to the traffic rails of the adjacent track section on each side of said track section. 80

31. In combination, a section of a railway track, a device for governing traffic movements in said section, a track circuit for said section, means controlled by a train adjacent said section in a first and a second direction from said section for controlling said track circuit, and means controlled by said track circuit for controlling said traffic governing device. 90

32. In combination, a section of railway track, a device for governing traffic movements in said section, a transformer connected across the rails of said section, means controlled by a train entering said section from a given direction for causing said transformer to supply periodically varied alternating current to the rails of said section in advance of said train, means controlled by a second train entering said section from a second direction for causing said transformer to supply constant alternating current to the rails of said section in the rear of said second train, a relay connected across the rails of said section and responsive to said periodically varied and said constant alternating currents, and means controlled by said relay for controlling said traffic governing device. 100

33. In combination, a section of railway track, a track circuit for said section including a source of current and the rails of said section, means for periodically varying the current supplied by said source according to a first or a second code, 110 a line circuit for said section including a second source of current, means for periodically varying the current supplied by said second source according to a first or a second code, means controlled by said track circuit for selectively controlling traffic movements in one direction in said section in a first or a second manner responsive to the first and second codes respectively of said line circuit. 120

34. In combination, a stretch of railway track divided into a plurality of sections, a track circuit for each of said sections including the track rails periodically varied at a first or a second code, a line circuit for each of said sections periodically varied at a first or a second 130 code, means controlled by said track circuits for selectively controlling traffic movements in a given direction in said stretch in a first or a second manner responsive to the first and second codes respectively of said track circuits, and means controlled by said line circuits for selectively controlling traffic movements in the opposite direction in said stretch in a first or a second manner responsive to the first and second codes respectively of said line circuits. 135

35. In combination, a section of railway track, a device supplying coded current to a given end of said section for controlling train carried apparatus for governing traffic movements in a first direction in said section, wayside apparatus controlled by said coded current for governing traffic movements in said first direction and in a second direction in said section, and a second device supplying a second coded current to a second end of said section for controlling train carried apparatus for governing traffic movements in said second direction in said section. 80
36. In combination, a section of railway track, a transformer connected across the rails adjacent a given end of said section for supplying current to said rails, an impedance transformer, a relay connected in series with the secondary winding of said impedance transformer across the rails adjacent a second end of said section, a code feeding transformer the secondary winding of which is connected in multiple with said relay and the secondary winding of said impedance transformer, means for at times opening the primary winding of said impedance transformer to increase the impedance in the secondary winding of said impedance transformer and so prevent operation of said relay by current from said code feeding transformer, means for at times short-circuiting the primary winding of said impedance transformer to permit operation of said relay by current from said first transformer, and means controlled by said relay and by current supplied to said section by said code feeding transformer for governing traffic movements in said section. 85
